UNITED STATES PATENT OFFICE

158,016

TIMING INSTRUMENT

Max E. Schlenker, Peru, Ill., assignor to General Time Corporation, New York, N. Y., a corporation of Delaware

Application September 8, 1949, Serial No. 4,909

Term of patent 14 years

(Cl. D42—7)

To all whom it may concern:

Be it known that I, Max E. Schlenker, a citizen of the United States, residing at Peru, in the county of La Salle and State of Illinois, have invented a new, original, and ornamental Design for a Timing Instrument, of which the following is a specification, reference being had to the accompanying drawing, forming a part thereof.

The figure is a perspective view of a timing instrument embodying my new design.

I claim:

The ornamental design for a timing instrument, substantially as shown.

MAX E. SCHLENKER.
